HERON A. SMITH AND LOUIS T. SMITH, OF SAN JOSE, CALIFORNIA.

SHOE-POLISHING DEVICE.

1,078,173.

Specification of Letters Patent. Patented Nov. 11, 1913.

Application filed February 5, 1913. Serial No. 746,343.

To all whom it may concern:

Be it known that we, THERON A. SMITH and LOUIS T. SMITH, citizens of the United States, residing at 353 South Fourth street, 5 San Jose, in the county of Santa Clara and State of California, have invented a certain new and useful Improvement in Shoe-Polishing Devices, of which the following is a specification.

- 10 Our invention comprises an improvement in shoe-polishing devices, and the objects of our invention are, first, to provide means for polishing either a tan or black leather shoe without discoloration from one to the other; 15 second, to provide a device of the character indicated that will be durable, simple, and economical. We attain these objects by the mechanism illustrated in the accompanying drawings, in which—
20 Figure 1 is a perspective view of our device with the polishing-pad swung outwardly on its pivots and in the act of revolving. Fig. 2 is a side elevation of our device with polishing pad nested and ready for use, a part being broken away. Fig. 3 is a sectional view on line "A—A" of Fig. 2.

Similar numerals refer to similar parts throughout the several views.

30 The main body portion 1, Figs. 1, 2, and 3, may be made of wood or any other suitable material, having two polishing pads attached thereto, one on each side thereof as shown at 2, Figs. 1, 2, and 3. These polishing-pads 2 may be made of felt or any other suitable material, preferably felt of the proper length, breadth and thickness. Said body portion 1 having holes bored in its two narrow sides and in approximately the center thereof as shown at 3, Figs. 1, 2, and 3.
35 Pad casing 4, Figs. 1, 2, and 3, may be made of metal or any other suitable material and is for the purpose of holding therein either

of polishing-pans 2 when not in use. At one end of pad casing 4 is fastened or worked a cylindrical tube 5, as shown in Figs. 1, and 45 2, in which a pivotal member, as 6, freely rotates. Said pivotal member 6, Figs. 1, 2, and 3, is preferably made of metal wire of the proper gage and length, and so bent and formed as to rotate freely in said cylindrical 50 tube 5, and to engage said holes 3 in said body portion 1, allowing said body portion 1 to revolve freely upon the ends of said pivotal member 6, as pivots, when said body portion 1 is swung free from said casing 4 55 as shown in Fig. 1. A notch, as shown at 7, Figs. 1 and 2, and of any required shape, is cut in the lower edge of each side of said casing 4 to permit the nesting of either pad 2 in said casing 4. 60

Having fully described our invention, what we claim as new, and desire to secure by Letters Patent, is—

In a shoe-polishing device of the character described, the combination of a body portion 65 having polishing pads attached thereto having a hole in approximately the center of each of the narrow sides of said body portion, a casing having a cylindrical tube fastened to one end thereof and a notch in the 70 lower edge of each side thereof, and a pivotal member formed to operate in said cylindrical tube and having extensions fitting in said holes in said body portion to pivotally connect the body portion of the casing, sub- 75 stantially as shown and described.

In testimony whereof we have signed our names to this specification in the presence of two subscribing witnesses,

THERON A. SMITH.
LOUIS T. SMITH.

Witnesses:

JOHN A. NAISMITH,
JNO. S. SANDERS.
